CLAIM

The ornamental design for a combined grill and table, as shown and described.

DESCRIPTION

FIG. 1 is a front perspective view of a combined grill and table showing my new design;

FIG. 2 is a corresponding perspective view thereof with the central grill element covered by a circular cover plate.

The characteristic feature of my design resides in the fact that the central grill element is selectively coverable by the circular cover plate member.

All sides are identical to the sides shown in FIGS. 1 and 2.

FIG. 2.
